UNITED STATES PATENT OFFICE.

ABRAHAM PRICE, OF TREORCHY, AND WILLIAM PRYSE, OF TRIORCHY, NEAR PONTYPRIDD, ENGLAND.

DETONATOR.

1,047,985.

Specification of Letters Patent. Patented Dec. 24, 1912.

Application filed March 21, 1912. Serial No. 685,211.

To all whom it may concern:

Be it known that we, ABRAHAM PRICE, timberman, and WILLIAM PRYSE, colliery fireman, subjects of the King of Great Britain, residing at 10 Sunny Bank, Cwmpark, Treorchy, and 41 Vicarage Terrace, Treorchy, near Pontypridd, Glamorganshire, England, respectively, have invented certain new and useful Improvements Relating 10 to Detonators, of which the following is a specification.

This invention has reference to devices for the insertion and withdrawal of detonators for shot firing purposes in mines and quarries and refers to that kind wherein a hollow tube is employed within which is adapted to slide a rod for the purpose of running the detonators into the charge.

Our improved device is designed more 20 particularly for use with the detonator shield described in the specification forming part of an application for Patent No. 665343.

The objects of the present invention are to 25 provide a device whereby the operations of inserting and withdrawing a detonator may be effected with perfect safety, to provide a device which is graduated in a standard of measurement so that the depth of the 30 shot hole may be seen and to provide a device adapted to be controlled solely by an authorized person so that the appointed shot firer only can charge and tamp the holes.

35 In order that our invention may be readily understood and carried into effect we will now describe the same fully with reference to the accompanying drawings in which:—

40 Figure 1 represents an elevation of a device constructed in accordance with our invention. Fig. 2 is a detail view hereinafter referred to.

In carrying our invention into practice 45 we provide a tubular member *a* having a stirrup or D shaped handle *b* the portion *b'* of which is provided with an aperture through which a rod *c* may be passed into the interior of the tube *a*. The rod *c* is 50 provided at its lower end with a detachable spike *d* which is secured thereto by an appropriate joint such as illustrated in Fig. 2. The joint shown is of the interlocking type. The rod *c* is provided at its lower end 55 with an extension approximately semi-cir-

cular in cross section having a longitudinally arranged slot cut near the top end thereof. The spike *d* is provided at its inner end with a reduced portion the bottom end of which fits into the semi-circular portion of the extension on the rod *c*. The end of the extension on the spike *d* has a longitudinally arranged projection adapted to engage with the above mentioned slot the whole being held in a locked position by 60 means of the tubular member *a*.

The opposite end of the rod *c* is provided with a disk *e* to form a scraper the purpose of which will be hereinafter explained. Means are provided whereby the rod *c* may 70 be locked within the tube *a* such as for instance by means of a cotter pin *f* adapted to pass through a slot in the top of the rod and to be secured in position by a padlock *g* the cotter of course being attached to the stirrup 75 shaped handle *b* such as by means of a chain as shown. The tubular member *a* is graduated in inches or other standard of measurement so that a record may be kept by the shot firer of the depth of the shot holes. 80

The operation of our improved device is as follows:—The rod *c* having been removed from the tube *a* by withdrawing the cotter *f* the detonator preferably contained in one of our improved shields before mentioned is 85 inserted in the end *a'* of the tube *a*. The end of the rod *c* (the spike *d* having previously been detached) is then placed behind the detonator and pushed through the tube taking with it the firing wires which are 90 connected to the detonator the ends of said wires protruding beyond the end of the tube *a* ready for connecting up to the electric cable. The detonator or detonator and shield then project slightly beyond the end 95 of the tube *a* and after inserting said detonator into the cartridge this latter is introduced into the shot-hole by means of the tube *a* the hole being then rammed with clay or other suitable material. After the 100 hole is rammed the depth is read off on the graduated scale on the tube *a* and the tube withdrawn the hole left thereby being stemmed for a suitable depth to exclude air 105 from the charge when the shot is fired electrically in the usual manner. Should a misfire occur the detonator with its shield is withdrawn by means of the firing wires. Our improved device is then fitted together 110 with the spike *d* in position and inserted

in the shot hole to the same depth as when the hole was charged the spike *d* entering the hole left in the base of the cartridge by withdrawal of the unexploded detonator. 5 This hole is opened out by the spike *d* the rod *c* and the spike *d* being then withdrawn leaving the tube *a* in position the scraper *e* at the end of the rod *c* is then used to clear out any loose stemming from the hole and 10 the detonator reinserted in the manner first above described the spring tongues or clips of the shield described in our aforesaid prior specification engaging the case of the cartridge and retaining it in position when 15 the tube *a* is withdrawn. The hole is again stemmed and fired in the usual manner.

It will be seen that with a device constructed in accordance with this invention the apparatus may be under control of one 20 shot-firer for the district thus preventing unauthorized tampering with the shot holes, while at the same time it provides a means whereby the detonators may be introduced

with perfect safety without risk of premature explosion by friction or otherwise. 25

We prefer to make all the parts of copper but any suitable metal or material may be employed.

What we do claim as our invention and desire to receive by Letters Patent is:— 30

A device of the type specified for the insertion and withdrawal of detonators for shot firing purposes in mines and quarries comprising a tubular member having a rod or plunger adapted to slide therein a detachable spike mounted at one end of said rod or plunger and means whereby the rod or plunger may be locked to the tubular member for the purposes specified. 35

In witness whereof we have signed this 40 specification in presence of two witnesses.

ABRAHAM PRICE.
WILLIAM PRYSE.
